UNITED STATES PATENT OFFICE.

ROBERT W. SCOTT, OF NEW YORK, N. Y., ASSIGNOR, BY MESNE ASSIGNMENTS, TO SCOTT & WILLIAMS, INCORPORATED, A CORPORATION OF MASSACHUSETTS.

MECHANISM FOR KNITTING REINFORCED FABRICS.

1,373,770.

Specification of Letters Patent.

Patented Apr. 5, 1921.

Original application filed September 11, 1916, Serial No. 119,331. Divided and this application filed June 29, 1917. Serial No. 177,702.

To all whom it may concern:

Be it known that I, ROBERT W. SCOTT, a citizen of the United States, and resident of New York, in the county of New York and 5 State of New York, have invented new and useful Improvements in Mechanism for Knitting Reinforced Fabrics, of which the following is a specification.

This invention relates to machine-knitting 10 sectionally spliced or reinforced fabrics with definite margins and either without projecting yarn-ends, or without such ends of undue length, on a series of instruments such as ordinary knitting machine needles.

15 Fabrics of this general nature have heretofore been produced only by reciprocatory knitting, in which case the traverse of the splicing yarn is limited to the width of a series of needles defining the spliced area, and 20 the margins of the spliced area are characterized by reversals of the splicing yarn.

When the knitting is tubular or circulatory, the spliced area has heretofore been defined by entering and withdrawing a splicing yarn from contact with the needles of 25 the desired series during progress of the knitting, or by causing a different movement of these needles only to enable them to take the yarn; or by clamping the splicing 30 yarn to break it, and releasing the broken end in contact with the body yarn, to cause it again to run in. In any of these cases the lateral margins of the spliced area are defined by the places of entrance and 35 withdrawal of the splicing yarn, or by the irregularly placed beginning and end of the clamped and broken yarn. At one or the other or both of these margins the splicing 40 yarn, when entered and removed from the needles, necessarily is cut or broken at a place more or less removed from the surface of the fabric, leaving an unsightly yarn-end of greater or less extent. Such entrance or removal of the yarn as a machine function necessarily involves the accurate timing 45 of the motion of either the splicing yarn or the needles or both, at entrance and removal of the splicing yarn. Such timing has seldom been secured of such accuracy as 50 infallibly to enter or remove the splicing yarn at the passage of the same needles for course after course, and when secured has necessitated mechanisms difficult to adjust and maintain in adjustment in the hands of

unskilled operators. When entry has been 55 by friction of the body yarn and removal by clamping or severing the running yarn, the margins of the spliced area have been irregular and uncertain.

When the splicing yarn is removed from 60 a tubular knit fabric at the margin of a reinforced area by any of the prior devices for forming such areas, the relative travel of the needles in respect of the severing means has heretofore determined that it shall be severed 65 from the fabric at a point distant from the fabric by at least the dimensions of the severing implement and a safe distance between it and the fabric; and in the case of the best practice, the severed supply-end 70 has been held or clamped for reinsertion at a point short of the severed end at the least by the dimensions of the clamping instrument.

An alternative and usual practice has been 75 to float a run of splicing yarn from exit point to entrance point, and thereafter to cut away this float, still leaving ends projecting from the fabric, and thus causing as 80 an additional defect a serious waste of the floated length of yarn.

The present invention has for its principal object to avoid the defective results above mentioned and thereby to provide for reinforcing a predetermined area of fabric 85 having definite margins at any desired longitudinal wales of the fabric, as well as to provide means for making at both the leading and following margin an edge of the reinforced area wholly free from projecting 90 ends of yarn, or from such ends of any substantial or detrimental length, said means being adapted to so operate as to use all and waste none of the splicing yarn.

Further objects are to provide machine 95 devices for the above purposes adapted to be employed in machines, for instance hosiery machines of existing kinds, without changes affecting the ordinary operation of the machine, and to provide such mechanism applicable to machines having dials. Other objects are to provide for the incorporation in the fabric of separate measured lengths or runs of reinforcing yarn during the continuous operation of the machine, and for 100 placing said measured lengths or runs in a predetermined relation to the needles and the fabric produced thereby. Still further 105

objects of the invention are to provide for accomplishing the above purposes without causing a repeated extensive movement of a yarn guide or guides, and to avoid the necessity for rapid movements of the yarn laterally into and out of contact with the needles. A further object is to enable the existing devices for changing, cutting and clamping yarns to be employed at the beginning and end of the formation of the spliced area to sever and hold the splicing yarn.

In pursuance of the above objects, my invention involves a new principle of operation. By creating a knitting wave in a series of knitting instruments and then feeding a main yarn and a splicing yarn at different angles of advance, so that between a selected pair of needles lying between a knitting wave and the point of exit from the yarn guiding means for the respective yarns, there is provided a separation between the knitting yarn and the splicing yarn enabling the splicing yarn to be (1) severed in place on the needles to end its insertion, and (2) seized in respect to the needles to begin its insertion. When the yarn is severed in this manner the cut-off end of the yarn then runs in a channel determined by the needle hooks, and the closed needle latches, if the machine is a latch needle machine. This end of yarn, now relatively stationary with respect to the running needles, stays in the channel so formed until the splicing yarn is again to accompany the knitting yarn when it is seized in respect to the needles by a device traveling with the needles operating as in the case of the cutting device between the knitting point proper and the yarn guides or fingers. The instruments both for cutting and for clamping the yarn in relation to the needles to again begin feeding it may be formed as a part of the usual web-holders, the vertical separation of the yarns enabling a sharpened edge on one severing web-holder (which is given an abnormally early movement of insertion) to take against and cut the splicing yarn between needle wales predetermined by the position of this web-holder in relation to the needles making said wales; and another web-holder at the beginning of the splicing area being adapted to seize or aid in seizing the end of yarn, as by having a splicing-yarn seizing notch therein, so that at an abnormally early projection of this seizing web-holder, the trailing end of the splicing yarn is grasped, the next following needle inevitably taking this end of the splicing yarn into the knitting wave proper.

In the accompanying drawings:

Figure 1 is a vertical central section of a knitting machine embodying devices illustrating the invention;

Fig. 2 is an under plan view of a web-

holder cam cap forming a part of said machine;

Figs. 3, 4, 5 and 6 are diagram internal developments of a series of needles employed in the said machine, illustrating the operation of certain instruments below to be described;

Figs. 7 and 8 are sections on the line 7—7 of Fig. 2 respectively showing the passage of instruments at the leading and at the following edges of the spliced area;

Fig. 9 is an end view of a modification of a yarn seizing web-holder;

Figs. 10 and 11 are diagrams illustrating the knitting of spliced and unspliced portions in the same course;

Fig. 12 is an elevation of a further modification of the yarn-seizing web-holder; and

Fig. 13 is an elevation of a fragment of the web-holder cam cap shown in Fig. 2.

Referring now to Figs. 10 and 11, the rotary needle cylinder circular machine selected for illustration is adapted to knit a tubular fabric by circular knitting on a series of needles rotating in the direction of the arrows *a* in said figures, and the invention will be described in connection with the production of fabric having a reinforced area *A* and a plain or body fabric area *B*, extending for a plurality of courses in the direction of the length of the fabric, upon such a machine. While the area *A* may be at any desired part, or separated parts, of the circumference of the tube, an illustrative instance of one area only is shown occupying about half of the tube. But it will be understood that the new instruments employed are adapted for use without change in straight and other types of machines making fabrics of various kinds, or in circular machines in which the yarn feed devices and cam carrier rotate with respect to a relatively fixed needle carrier.

Referring to Fig. 1, the needles *n* of any desired sort, shown as latch needles, may be suitably mounted in a needle carrier 260 and actuated by the usual knitting cams (not shown) on a cam carrier 270 in the usual manner to produce a length of fabric or a knit article such as a stocking.

Coöperating with the needles *n* and held to slide in the radially grooved bed 295 the usual web-holders *w* are provided to perform their customary function. As illustrated in Figs. 1 and 2 a web-holder cam cap 300, held relatively stationary with respect to the rotating needles and web-holders, comprises a withdrawing cam 306 and adjustable advancing cams 309, 309' acting upon butts *w'* of the web-holders *w* to move them out and in with respect to the retracting and advancing needles. The normal wave caused by cams 306 and 309 when the machine is employed in circular knitting, relative travel of the web-holder butts be-

ing in the direction of the arrow *b*, Fig. 2, is illustrated by the broken line *W*, Fig. 2.

The lowest draft of the needles actuated to knit by the active stitch cam takes place in relation to the wave of movement in the web-holders about at the point *k* illustrated in Figs. 2, and 3 to 6.

As now usual in such machines, any desired series of the web-holders *w* may be arranged to be moved in at an earlier time than the normal, to predetermine a longer stitch, a movable cam 312 being provided on cap 300 to engage extra long butts (not shown) of some of the web-holders for that purpose. When this cam is inwardly positioned (for instance, by the means fully shown in my Letters Patent No. 1,152,850, dated September 7, 1915, for this purpose), the longer web-holders move inward on the line *W'*, Fig. 2, at an earlier time than the normal web-holders, to determine longer stitches. The stitches throughout areas A may be lengthened by this means.

Yarn is fed to the needles from a yarn feed opening or throat, which may be the upper side of a channel plate *f* adapted to determine the lower operative position, under stress of spring 8, of a series of yarn feed fingers *F* pivoted at 554. One of these, as that finger *F'* nearest the observer in Fig. 1 and at the left in Figs. 3 to 6, carries a splicing yarn *s*, the finger *F'* being associated with means for clamping its yarn, as by having a foot 2 adapted to stand on the throat-plate *f* and clamp the yarn *s* between said plate and the foot 2.

Another one of the fingers *F* as usual carries the main or body yarn *y*. The yarn *y* and yarn *s* are by the above (or any preferred) means fed to the needles at a different lead or angle of advance, splicing yarn *s* being fed from a point nearer the knitting point *k* than the body yarn *y* (see Figs. 3 to 6).

The yarn fingers or guides *F*, *F'* may be lifted at times to inoperative positions by the operation of suitable automatic means, such as one of the thrust bars 460 resting at their lower ends on a pattern surface or drum 120 having cams for lifting the bars 460 and guides *F*, *F'* to an upper inoperative position as shown at 5, Fig. 1, and when any of the guides is so positioned its yarn, thereby removed from the fabric, is carried into a suitable severing device and clamp, such as the guide 604, clamp 602, and shears 608 operated by the lever 611 and a thrust bar 460 from the pattern surface, which parts may be constructed and operate as shown in my said Patent No. 1,152,850.

Means are provided for clamping and releasing the splicing yarn *s* while its movable guide remains in an operative position. Thrust bar 460 for the splicing yarn finger *F'*, for instance, may be provided with a lug

d, which when the pattern drum 120 permits the bar 460 to rest, as shown, in a lower position normally clamping the splicing yarn *s* against the plate *f*, lies in the plane of a cam 296 attached to and rotating with the web-holder bed 295. This cam may be constructed substantially as shown in Fig. 29 of my said Patent No. 1,152,850, with adjustable ends, whereby accurately and adjustably to determine with respect to the series of needles *n* the position at which the lug *d* will be moved by the cam 296. When the lug *d* is so moved, bar 460 rocks on the adjustable stop *e* resting on comb 451, and near the end of its movement away from the center of the cylinder 260 encounters a cam surface *h* on the guide *F'* thereby lifting the foot 2 slightly above the plate *f* to release the yarn *s*.

If desired, any suitable or known device operating on the yarn *s* to slacken it when it is not being fed may be employed between the source of supply and the clamp 2, *f*.

The splicing yarn may be originally entered upon the needles in any ordinary or usual manner, for instance by moving the splicing yarn finger *F'* from the position shown at 5, the splicing yarn then being held in the clamp 602, down to the operative position shown in Fig. 1, this movement being occasioned by pattern surface 120 and occurring when the cam 296 is positioned to hold the foot 2 away from the plate 5 to permit the splicing yarn to be entered and to pass into the knitting wave as usual. At 100 this initial entrance of the splicing yarn a single projecting end of yarn *s* representing the yarn extending to the clamp 602 is left on the inside of the fabric.

At predetermined places among the needles, instead of one of the web-holders *w*, one or more severing web-holders *X* each having a web-holder notch *w³*, a beak *w⁴* and a sharpened upper surface *w⁵* is placed in a groove in the bed 295 between two of the needles (Figs. 3 to 6, and 8). Referring to Figs. 3 and 4, this severing web-holder is adapted to be operated for the ordinary web-holder functions with respect to the yarn *y*, but by reason of the difference in lead between the yarn *y* and the yarn *s* the beak *w⁴* is adapted to take between the splicing yarn entering the needles and the body yarn *y* entering the needles upon giving the severing web-holder an inward movement at an earlier time than the normal inward movement of the web-holders. The action of the needles thereafter serves to draw against its upper sharpened surface *w⁵* that portion of the yarn *s* taken between two adjacent needles. The result is to sever the splicing yarn between two predetermined needle wales, as illustrated in Fig. 4, the leading severed end *s²* being immediately bound into the knit stitch beginning 130

to be formed when the severing operation takes place. For clearness, Figs. 3 to 6 do not show the previously knit courses.

The following severed portion s^3 is left 5 free in the hook of the leading needle n' of those needles upon which reinforced fabric is not to be formed. The severing action may be and preferably is aided by permitting the yarn guide F' to clamp the splicing 10 yarn by means of its foot 2 at this time, the lug d then running off the adjustable rear end of the cam 296. In some cases, however, a suitable tension on the yarn s may be employed, the devices for clamping 15 and slackening the yarn s being dispensed with.

The end s^3 of the yarn s having been cut by the described means at a predetermined place with respect to the yarn guide F' , and 20 the end of the yarn s being clamped, the said end s^3 then lies in the hooks of the needles n , and in a virtually tubular passage defined by the closed latches of the needles traveling down the knitting-wave 25 and the nearby hooks of the web-holders w . No ordinary movement of the machine can withdraw the yarn end s^3 so positioned, further relative movement of the needles with 30 respect to the guide F' occurring without changing the position of the end s^3 (Figs. 4 and 11), which remains in contact with the needles during the knitting of the yarn y alone for the remainder, or any desired part of the remainder, of the course.

35 To enable the yarn s again to be fed beginning at a predetermined needle without any appreciable projecting end, the machine is also provided with a seizing web-holder Y , best shown in Fig. 7, at the leading edge of 40 each area A. This instrument has a yarn throat w^3 functioning as an ordinary web-holder, and a beak w^7 , preferably somewhat higher than the corresponding beak w^4 of the severing web-holder, and a second beak 45 w^8 , separated by a notch w^9 between the beaks and at a height to take over the end s^3 of the yarn s lying in the described relation to the needles. If the seizing web-holder Y is now given an inward movement 50 at an earlier time than the normal web-holders, the end s^3 of the splicing yarn taken in the notch of the seizing instrument will be bent around the leading needle n^2 of that series upon which reinforced fabric is to be 55 knit, and so determine the entrance of the splicing yarn and the margin of the spliced area A at the wale from this predetermined needle n^2 . This action may be aided by causing the needle n^2 and the seizing web-holder Y to clamp the end s^3 of the yarn s between them. One way of doing this is 60 illustrated in Fig. 5, the needle n^2 being bent to the left as shown, to rub against one face of the seizing web-holder Y . Alternatively, as 65 illustrated in Fig. 9, the web-

holder Y may be laterally offset to the rear with respect to the direction of motion of the needles as shown, so as to rub against and clamp the yarn with respect to a straight leading needle n^2 ; or a comparatively thick 70 seizing web-holder Y may be employed between normal needles.

As shown in Fig. 12, a modified form of seizing web-holder Y' may be employed having a notch 10 on its relatively high top 75 12, and a beak 14 at the same height as the beak w^7 of the form above described. Seizing web-holder Y' is adapted to be moved forward a shorter distance than the web-holder Y , the downward movement of the 80 needle n^2 taking the yarn-end s^3 against its side face, with the same effect as above described.

Referring now to Figs. 10 and 11, the relative location of the knitting wave k and 85 the yarn guides F' and F being as shown, the place of actuation of the severing web-holder X may be at the point C, and the place of operation of the seizing web-holder Y may be at the point H, both lying between 90 the knitting point k and the respective yarn guides.

Inasmuch as both the seizing web-holder and the severing web-holder travel with the 95 needles, clamping of the yarn end s^3 with respect to the needle n^2 insures entrance of the splicing yarn at the wale from this needle, and the manner of performing the operation insures a minimum length of the 100 end s^3 with respect to the surface of the fabric. In practice, this end may be so short as to be buried in the ensuing stitch taken on the needle n^2 . The length of this end is determined by the relative position 105 of the points C and H, or by the relative time of opening of clamp 2, f , or by both.

Whenever the seizing web-holder Y is operated the splicing yarn may be released by the operation of thrust bar 460 and cam 296 to open clamp 2, f . The relative times of 110 releasing the yarn s and actuating the seizing web-holder Y are accurately related by rotation together of the parts Y and 296 as attachments of the bed 295.

At the longitudinal end of the spliced 115 area, the yarn guide F' is moved to the position shown at 5 by the action of the cam surface 120 on its thrust bar, and the yarn s is received by the guide 604, clamped at 602 and cut at 608 until it is desired again to 120 splice a part of the tube, when the operation is repeated.

Any desired means may be employed for giving the described movements to the seizing web-holder and the severing web-holder, 125 but I prefer the means shown in Figs. 2, 7 and 8, comprising tails w' and y' at different vertical positions on the respective severing web-holder X and seizing web-holder Y , and suitably positioned cams 130

- and 26 respectively operating the severing and seizing devices. As shown, these cams may be mounted on any suitable part such as the web-holder cap 300, and preferably 5 are arranged for independent adjustment radially and circumferentially. For instance, a circumferential upturned portion 27, 28 of each cam may be slotted for a common holding screw 29, the respective 10 parts being spaced from each other and the cam cap by washers 30, the part 28 of cam 26 having a screw 31 for independently clamping it, and a screw 33 in the cam cap free in slots 34 of different widths in parts 15 27, 28, for radially adjusting part 28 and cam 26 only. Cam 25 may be independently radially adjusted by a large headed screw 31 in the slots 34, the mounting parts 27, 28 of both cams being slightly resilient. 20 When the cams are adjusted, the beaks of the severing and seizing web-holders move inwardly under the influence of the respective cams 26 and 25, at the proper time, for instance as shown at x^2 and y^2 in Fig. 2.
- 25 What I claim is:
1. A knitting machine having therein needles, means operating on the needles to knit thereat, means adapted to guide a plurality of yarns to the needles simultaneously 30 and in different operative positions in relation to the needles, in combination with means for severing one of said yarns only at the needles and while said yarn is in its normal operative position, whereby to end 35 the inclusion of said yarn at a predetermined place in respect to and within a predetermined loop of the fabric, and means for subsequently causing the needles to take the severed end of the yarn.
  - 40 2. A knitting machine having therein needles, means operating on the needles to knit thereat, means adapted to guide a plurality of yarns to the needles simultaneously in different positions, means for severing 45 one of said yarns at the needles to end its inclusion in the fabric, and means for seizing in respect to one of the needles the severed end of the yarn to determine its further insertion.
  - 50 3. A knitting machine having therein needles, means operating on the needles to knit thereat, means adapted to guide a plurality of yarns to the needles simultaneously in different positions, means for severing 55 one of said yarns between adjacent needles to end its inclusion in the fabric, and means adapted to coöperate with one of the needles to seize the severed end of the yarn between said needle and said means to determine its further insertion.
  - 60 4. Sectional splicing means for knitting machines comprising in combination a yarn-guide adapted to be maintained in operative position during knitting of a section of fabric containing the spliced area, a series of 65 needles, means adapted to cause a certain needle of said series to seize a free end of the splicing yarn fed by said guide, and means for severing the said splicing yarn in place on the series of needles to end its 70 inclusion in the fabric and provide a free end for repeating the operation.
  5. Sectional splicing means for knitting machines comprising in combination a series of needles, a body and a splicing yarn-guide 75 both adapted to be maintained in operative position to feed their yarns at different angles to said needles during knitting of a section of fabric containing the spliced area, means working at the position taken by 80 the splicing yarn to cause a needle at one place in said series to seize an end of the splicing yarn fed by said splicing yarn-guide, and means acting on the yarns at the needles for severing the said splicing yarn 85 only in place on the series of needles at another place.
  6. Sectional splicing means for knitting machines comprising in combination a yarn-guide adapted to be maintained in operative 90 position during knitting of a section of fabric containing the spliced area, a series of needles, means adapted to cause a needle of said series to seize an end of the splicing yarn fed by said guide, means for severing 95 the said splicing yarn at another place in the series of needles, and means for clamping the severed yarn in respect to its yarn-guide the severed end remaining in trailing contact with the needles.
  7. Yarn feeding means for knitting machines comprising in combination a yarn-guide adapted to be maintained in operative position during knitting of a section of fabric containing the yarn therefrom, a series of needles, means adapted to cause a predetermined needle of said series to seize an end of the yarn fed by said guide, means for severing the said yarn at another place 100 in the series of needles, means for clamping the severed yarn, whereby to trail the end thereof in contact with the needles, and means for releasing the said clamping means upon seizure of the yarn.
  8. A knitting machine having therein a 115 series of needles and means for knitting on said needles and yarn severing means acting to sever a yarn between adjacent needles of said series and substantially in the plane of the fabric.
  9. A knitting machine having therein a 120 yarn severing means acting to sever a yarn between a predetermined pair of adjacent needles adapted to be actuated to knit and substantially in the plane of the fabric.
  10. A knitting machine having therein, in combination, needles and means for operating them to knit a plurality of yarns, and yarn severing means coöoperating with one of the yarns where it lies in knitting posi- 130

- tion upon a number of adjacent needles being retracted to knit at a predetermined place in respect to the needles, whereby to cause the severed end to lie in the plane of
5 the knit fabric.
11. A knitting machine having therein a series of needles and means for operating them to knit a plurality of yarns, and means for severing one of said yarns while lying
10 in knitting position on said needles at a predetermined place in and on the series of needles.
12. A knitting machine having therein needles and a yarn severing web-holder co-
15 operating with needles actuated to knit to sever a yarn at the needles.
13. A knitting machine having needle and cam-carriers adapted for relative movement, and a yarn-severing device operating on
20 yarn on the needles fixed in the direction of said relative motion with respect to the position of active needles in the needle-carrier.
14. A knitting machine having a rotary
25 needle carrier and a yarn severing device rotating therewith in position to sever a yarn between certain adjacent needles.
15. A knitting machine having in combination needles, web-holders, and a yarn-
30 severing web-holder adapted to sever a yarn between adjacent needles.
16. A knitting machine having in combination needles, web-holders, and a yarn-
35 severing web-holder adapted to sever a yarn between adjacent needles and to hold down the web knit of another yarn.
17. A knitting machine having therein web-holders and means to actuate them, one of said web-holders having thereon means
40 for severing a yarn, and means for moving said severing web-holder differently from one or more of the other web-holders.
18. A knitting machine having needles and means associated with the needles for
45 seizing at a particular needle a free end of yarn trailing in contact with the needles.
19. A knitting machine having needles and means co-operating with a predetermined needle only to cause said means and needle to take and hold for knitting a free end of 50 yarn.
20. A knitting machine having needles, web-holders, and a yarn-seizing web-holder adapted to cause entrance of a free end of 55 yarn trailing at the needles.
21. In a knitting machine, a yarn-seizing web-holder having thereon means adapted to co-operate with a needle to hold an end of yarn.
22. A knitting machine having in combination needles and a yarn-guide adapted to hold in trailing contact with the needles a loose end of yarn, and means associated with a predetermined needle to cause said needle to seize and knit said loose end of 60 yarn.
23. A knitting machine having therein web-holders and means to actuate them, one of said web-holders having thereon means for seizing a yarn, and means for moving 70 said seizing web-holder differently from one or more of the other web-holders.
24. A knitting machine having in combination needles, a yarn-guide, a pattern operated connection for moving said yarn-guide to and from an operative position, means for clamping the yarn, and means co-operating with said connection to release the yarn supplied by said yarn-guide while in said position. 75
25. A knitting machine having in combination needles, a yarn-guide, a pattern operated connection for moving said yarn-guide to and from operative position, and means relatively fixed in respect to the needles co-operating with said connection to clamp and release the yarn supplied by said yarn-guide while in said position at the passage of predetermined needles. 80 85

Signed by me at New York, N. Y., this 90
26th day of June, 1917.

ROBERT W. SCOTT.
